UNITED STATES PATENT OFFICE

CHARLES J. GRIFFITH, OF ST. LOUIS, MISSOURI

RAILWAY STRUCTURE

Application filed August 6, 1927, Serial No. 211,116. Renewed May 11, 1929.

This invention relates to railway structures. It has for its objects to produce a simple and comparatively inexpensive, yet practically efficient, safe and durable track tie and rail fastening means, and to attain certain advantages as will hereinafter more fully appear.

The invention consists in the novel metallic structure and in the parts and combinations 10 and arrangements of parts hereinafter specified and afterwards pointed out with particularity in the appended claims.

In the accompanying drawings forming part of this specification and illustrating a 15 practical adaptation of the invention:—

Figure 1 is a cross section through a railway track in the region of a cross tie thereof, the tie being shown partially in side elevation and partially in section substantially 20 on the line 1—1 of Figure 2, and one of the rail fastening blocks being shown in section, the other being shown in side elevation;

Figure 2 is a top plan view of the cross 25 tie, one of the track rails being shown fastened in place thereon, and the opposite end portion of the tie being uncovered to show the relative arrangement of the rail seating portion and the sockets for the rail fastening 30 blocks;

Figure 3 is a cross section on the line 3—3 of Figure 1;

Figure 4 is a face view of the rail seat pad 35 detached to show the details thereof; and

Figure 5 is a fragmentary view, on an enlarged scale, partly in section and partly in side elevation, to illustrate the correlation and co-action of the rail base, seat pad and fastening block.

Referring now to the drawings, the numeral 1 designates generally the cross tie, which, according to the present invention, is preferably constructed throughout of metal and may be produced by any approved method 45 such as casting, rolling, forging or pressing;

the metal, of course, to be of rust resisting character and possessing the requisite strength for durability and safety. The tie may be produced in different shapes, both crosswise and longitudinally, and be relatively light in weight by eliminating all excess or unnecessary material and making it rigid by suitably flanging and ribbing the structure.

As shown, the tie 1 is substantially inverted T-shaped in cross section throughout its middle portion, or, in other words, it has a base flange 2 and a central upstanding longitudinal rib or flange 3. The base flange 2 extends to the ends of the tie where it merges with the vertical end flanges 4, which latter merge 50 with top flanges 5, said top flanges extending inward some distance beyond the seat portions for the track rails to be presently described.

The body of the tie 1, in the region of the 55 rail seats and fastening devices to be later described, is thickened and proportionately increased, as at 6.

Extending transversely of the tie 1 are 60 channels 7 in which the track rails 8 are seated, while on opposite sides of the channels 7 are sockets 9 in which are inserted the rail fastening blocks 10, the outer end portions of said blocks 10 being bevelled, as at 65 11, and the adjacent end walls of the sockets 75 9 being correspondingly upwardly flared or inclined.

At the ends of the blocks 10 are lips or 70 flanges 12 which overlie the base flanges of the rails 8 in rather snug contact therewith, while below said portions 12 are lugs 13 which underlie said base flanges of the rails and are preferably spaced, at least slightly, therefrom, as more clearly shown in Figure 5 of 75 the drawings, as at 14, in order to permit limited downward movement of the rails 8 without the latter coming in contact therewith.

In each of the blocks 10 is an aperture for 80 the reception of a securing bolt or screw 15,

which latter, as shown in the drawings, is inserted into a screw-threaded aperture provided therefor in the body of the tie.

Preferably, a pad 16 is interposed between the base flange of the rail 8 and the bottom of the channel or seat portion 7 of the tie 1, so as to serve as a sound deadener and cushion for the rail. This pad is preferably composed of a characteristic metal or alloy different from that of which the body of the tie 1 is composed and possessing a certain amount of inherent resiliency and sound deadening qualities and yet being capable of withstanding the usage to which it is put in the structure and being resistant to the corrosive action of the elements.

As shown more clearly in Figure 4 of the drawings, this pad 16 is of general rectangular form, but it is provided at its opposite side marginal portions with notches 17, into which notches are received the lugs 13 of the blocks 10, by which arrangement the pad is securely held from endwise movement in the channel or seat portion 7 of the tie. In this connection, it may be here stated that by the provision of the clearance space 14 between the lug 13 of the block 10 and the under side of the base flange of the rail 8, the latter always rests solely on the pad 16 even should a certain amount of wear occur due to the action of the rail on the pad under the weight of the trains passing thereover, and this clearance, of course, is provided principally to permit the pad to function yieldably as a cushion under the same conditions.

By the peculiar formation of the fastening blocks 10 they are easily inserted into the sockets 9 by first placing the pad 16 in the channel or seat portion 7 of the tie, setting the rail in place thereon, thence placing the block with its lip portion 12 on top of the base flange of the rail at an angle and then sliding it forward and at the same time dropping the bevelled end portion 11 of the block, during which manipulation the lug 13 enters the notch 17 in the pad 16 and underlies the base flange of the rail, and when the block is finally seated in the socket 9 the bolt or screw 15 is applied to hold the block in place. Preferably, a suitable lock-washer 18 is interposed between the head of the bolt or screw and the top face of the block 10 so as to resist any action tending to loosen the bolt or screw. While the side faces of the block 10 may be substantially perpendicular or square with the top and bottom faces thereof it is preferable to slightly taper or bevel the side faces in order to facilitate the placing of the block in and removing it from the socket 9, the side walls of said socket, of course, being correspondingly inclined.

On opposite sides of the sockets 9 the tie 1 may be provided with recesses 19, which, as shown, are rounded out, but they obviously may be of other form. These recesses afford

clearance for convenience in applying tongs or other suitable implements to remove the blocks from the sockets.

It is to be particularly noted that when the blocks 10 are in place in their respective sockets the track rails 8 are securely held against tilting laterally owing to the interlocking therewith of the projections 12 and 13 of the blocks 10 and the fact that the adjacent squared end portion of the block bears against the corresponding square end portion of the socket 9. This relieves the securing bolts or screws 15 of considerable strain. At the same time, when the securing bolt or screw 15 is removed it is a very easy matter to remove the block 10 by lifting its beveled end portion 11 first.

From the foregoing it is clearly apparent and obvious that a simple and practical structure is produced which has all the advantages of the ordinary wooden and metallic ties and considerable further advantage thereover.

Obviously, the structure may be modified and changed in many respects without in the least departing from the spirit and scope of the invention as defined by the appended claims. The invention, therefore, is not limited to the specific construction and arrangement shown in the accompanying drawings.

What is claimed is:

1. In a railway structure, a cross tie having a transverse rail seating channel therein, said tie having a socket contiguous to said rail seating channel, and a rail securing device comprising a block insertable in said socket and having a retaining lip to overlie the base flange of a track rail seated in said channel and a lug below said lip to underlie said base flange of the track rail in spaced relation thereto.

2. In a railway structure, a cross tie having a transverse rail seating channel therein, said tie having a socket contiguous to said rail seating channel, the inner end wall of said socket being substantially perpendicular and coincident with the adjacent wall of said channel, and the outer end wall of said socket being upwardly flared, and a rail securing device comprising a block whose body portion is a counterpart of said socket and being detachably insertable therein, said block having a lip to overlie the base flange of a track rail seated in said channel and a lug below said lip to underlie said base flange of the track rail, and means for detachably securing said block in said socket.

3. In a railway structure, a cross tie having a transverse open-ended channel in its top face and a socket contiguous to said channel and communicating at its adjacent end with said channel, a rail supporting pad seated in said channel and having a notched side marginal portion, and a retaining device comprising a block seatable in said socket and having a lip to overlie the base flange of a

track rail seated on said pad and within said channel and a lug below said lip to enter said notched portion of the pad and underlie said base flange of the track rail and being spaced from the latter.

5 4. In a railway structure, a cross tie having a transverse open-ended channel in its top face and a socket contiguous to said channel and communicating at its adjacent end with 10 said channel, said socket being deeper than said channel, its end wall adjacent to said channel being substantially perpendicular and its opposite end wall being upwardly flared, a rail supporting pad seated in said 15 channel and having a notched side marginal portion, and a retaining device comprising a counterpart body portion seatable in said socket and having a lip to overlie the base flange of a track rail seated on said pad and 20 within said channel and a lug below said lip to enter said notched portion of said pad and underlie said base flange of the track rail and being spaced from the latter, and means for detachably securing said retaining device in 25 said socket.

5. The combination of an all metal railway tie, said tie comprising a horizontal base flange, a central longitudinal upstanding flange extending throughout the middle portion 30 of the tie, the end portions of the tie merging with said upstanding flange and being relatively increased in width of body and being marginally flanged horizontally at the top and vertically at the extreme outer 35 ends thereof, the top portions of said increased end body portions being provided with transverse open-ended rail-seating channels and sockets contiguous to and on opposite sides of said channels in correlation thereto 40 to receive and hold rail-retaining elements.

6. The combination of an all metal railway tie having a transverse open-ended rail seating channel therein and a socket contiguous to said channel, said socket communicating 45 with said channel through the adjacent side thereof and being deeper than said channel, the end wall of said socket adjacent to said channel being substantially perpendicular 50 and its opposite end wall being upwardly flared, a rail supporting pad in said channel and having a notched side marginal portion opposed to said socket, a retaining device comprising a body portion that is a counterpart 55 of said socket, said body portion having an aperture therethrough to register with an aperture in the tie that communicates with the bottom of said socket, said body having a lip to overlie the base flange of a track rail 60 seated on said pad and within said channel and a lug below said lip to enter said notched portion of said pad and underlie the base flange of said track rail and being spaced from the latter, and a bolt insertable in said 65 apertures in said retaining device and the tie

for detachably securing said retaining device in said socket.

7. A railway tie having a transverse channeled rail seat and a socket contiguous to and communicating with said seat, and a rail retaining device comprising a counterpart 70 body portion seatable in said socket and being substantially flush with the top thereof, said tie having communicating recesses on opposite sides of said socket to afford clearance for the application of a tool to remove said rail retaining device from the socket. 75
